INSULATING MATERIAL

Clarence M. Tuck, Bellevue, Wash.

Application February 19, 1951, Serial No. 211,729

10 Claims. (Cl. 2—97)

My present invention relates to an improved insulating material of the type especially adapted for use in clothing, bed coverings, sleeping bags and the like, where as in extreme climates it is imperative to retain warmth while permitting body respiration.

This application is a continuation in part of my application, Serial No. 687,811, filed August 2, 1946, now abandoned.

Experience has shown that heavy weight of cloth or fabric does not result in a high rate of heat retention and further such garments as are now available are bulky and cumbersome and do not permit freedom of movement of the wearer.

It is therefor my principal objective to offer a cloth for clothing and the like made up of two layers of light-weight material with the inner side of the outer layer overlaid with sections of heat reflecting material so arranged as to permit air movement therethrough to permit respiration of the body while retaining body heat.

In the accompanying drawings I have illustrated one complete example of the physical embodiment of my invention according to the best mode I have thus far devised but it will be understood that various changes and alterations may be made in the exemplified structure within the scope of the appended claims.

In the drawings:

Figure 1 is a front view of a jacket embodying the construction of my invention;

Figure 2 is a plan view showing the sections overlying one layer of material;

Figure 3 is a detail view showing partial rows of sections to illustrate the overlapping arrangement;

Figure 4 is a detail view showing spaced sections of reflective material; and

Figure 5 is a sectional view at line 5—5 of Figure 3.

Referring now to the drawings wherein I have illustrated the present preferred embodiment of my invention I have shown the construction as applied to a jacket 2 having sleeves 4 and 6 and a collar 8, all of conventional design and construction.

The material of the jacket consists in an outer layer of fabric 10 and an inner layer of fabric 12, of suitable lightweight cloth as desired which may be treated or processed for waterproofing as appears desirable.

On the inner surface of the outer layer 10 I secure pieces or sections of heat reflecting material 14 which may be metal foil such as aluminum, lead or chromium, or other suitable metallic foil which possesses flexibility and heat reflecting characteristics. The foil should be polished to most effectively reflect the body heat of the wearer and the sections may be of various sizes and shapes.

In this embodiment I have shown the sections as rectangular and arranged in rows 16, the ends of adjoining sections overlapping as at 18 and I use a series of rows, the lower edges of the sections of each upper row overlapping the upper edges of the lower row as at 20.

The sections of the rows and the series of rows are stitched to the fabric 10 as at 22, the stitches running from diagonally opposed corners of the overlapping sections and through the centers thereof. In this manner each corner of each section is secured and the four edges of the sections are not secured so that air movement is permitted in the directions indicated by the arrows. For use in moderately cold weather the spaced apart sec-

tions as illustrated in Figure 4 give a more flexible shield means with greater porosity.

In other words, air may pass under each section along two edges, and over each section along the other two edges. By overlapping the sections, a solid surface heat reflecting body is interposed between the inner and outer fabrics and the heat normally generated and given off by the body will be reflected back by the overlapping foil sections to make optimum use of such body heat to maintain normal body temperatures.

It has also been discovered that lighter color in the foil sections is conducive to a minimum retention of heat by the sections and it is possible that other material than foil having similar characteristics may well be employed. In addition, suitable material sections may be sprayed or otherwise coated with metal to obtain heat reflecting qualities.

From the above description it will be apparent that the material of my invention will afford a highly reflective surface which may be used in lightweight fabric layers to provide lightweight clothing for use even in extreme conditions as found in Arctic regions, and the loss of heat through such a garment and the consequent suffering from cold will be lower than in any known material. The sections 14 may be square, as shown in Figures 2 and 4, or may be elongated, as shown in Figure 3. Their edges may run horizontally and vertically, or may run diagonally, as shown in Figure 2. In Figure 3 the overlapped vertical edges are staggered.

Having thus fully described my invention what I claim as new and desire to secure by Letters Patent is:

1. An insulating material for garments comprising: an inner and an outer layer of cloth pervious to air, and a heat reflecting surface on the inner surface of said outer layer comprising a multiplicity of overlapping square sections of metal foil arranged in overlapping rows and secured thereto by stitching running diagonally of the sections, said sections having their adjacent edges disposed in lapping relationship one to another with the lower edges of the upper sections overlapping the upper edges of adjacent lower sections on the side of said sections facing said inner layer.

2. An insulating garment comprising: an inner and an outer layer of cloth pervious to air, and a heat reflecting surface on the inner surface of the outer layer comprising a multiplicity of square sections of metal foil arranged in diagonal rows and secured to said outer layer of cloth by horizontal and vertical stitching passing through the corners of said sections, said sections having their adjacent edges disposed in lapping relationship one to another, with the lower edges of upper sections overlapping the upper edges of adjacent lower sections on the side of said sections facing said inner layer.

3. An insulating material forming a wall of a garment, comprising: an outer layer of cloth, and a heat reflecting surface on the inner surface of said outer layer comprising a multiplicity of independent rectangular sections of metal foil arranged in ranks and files and secured to said outer layer by stitching running diagonally of the sections, said sections having all of their adjacent edges disposed in lapping relationship one to another with the lower edges of upper sections overlapping the upper edges of adjacent lower sections on the side of said sections opposite said outer layer.

4. An insulating material forming a wall of a garment, comprising: an inner and an outer layer of cloth, and a heat reflecting surface between said layers comprising a multiplicity of independent rectangular sections of metal foil arranged in ranks and files and secured to one of said layers by stitching running diagonally of the sections, said sections having all of their adjacent edges disposed in lapping relationship one to another with the lower edges of upper sections overlapping the upper edges of adjacent lower sections on the side of said sections facing said inner layer.

5. An insulating material forming a wall of a garment, comprising: an inner and an outer layer of cloth pervious to air, and a heat reflecting surface on the inner surface of the outer layer comprising a multiplicity of independent rectangular sections of metal foil arranged in

ranks and files and secured to said outer layer of cloth by stitching extending diagonally of the sections and passing through the corners of the sections, said sections having all of their adjacent edges disposed in lapping relationship one to another with the lower edges of the upper sections overlapping the upper edges of adjacent lower sections on the side of said sections facing said inner layer.

6. An insulating material forming a wall of a garment, comprising: an inner and an outer layer of cloth and a heat reflecting surface on the inner surface of the outer layer comprising oblong rectangular independent sections of metal foil arranged in a series of horizontal rows and a series of rows extending laterally of the horizontal rows secured to the cloth by stitching diagonal of the sections through their corners, the lower edges of upper sections overlapping the upper edges of adjacent lower sections on the side of said sections facing said inner layer.

7. An insulating material forming a wall of a garment, comprising: an inner and an outer layer of cloth pervious to air, and a heat reflecting surface between said layers comprising a multiplicity of independent rectangular sections of metal foil arranged in ranks and files and secured to one of said layers, said sections having all of their adjacent edges disposed in lapping relationship one to another with the lower edges of upper sections overlapping the upper edges of adjacent lower sections on the side of said sections facing said inner layer.

8. An insulating material forming a wall of a garment, comprising: an outer layer of cloth pervious to air, and a heat reflecting surface on the inner surface of said outer layer comprising a multiplicity of independent sections of metal foil arranged side by side and one above another, said sections having all of their adjacent edges disposed in lapping relationship one to another, and means

attached to said layer of cloth and to said sections securing the sections in place.

9. An insulating material forming a wall of a garment, comprising: an inner and an outer layer of cloth pervious to air, and a heat reflecting surface on the inner surface of the outer layer comprising a multiplicity of independent rectangular sections of metal foil arranged in ranks and files and secured to one of said layers by stitching extending diagonally of the sections through their corners, the edges of the sections intermediate said corners being free from the layer to which the corners are secured.

10. An insulating material forming a wall of a garment, comprising: an outer layer of cloth pervious to air, and a heat reflecting surface on the inner surface of said outer layer comprising a multiplicity of square sections of metal foil arranged in ranks and files and secured to said outer layer by stitching running diagonally of the sections through their corners, said sections having all of their adjacent edges disposed in lapping relationship one to another with the lower edges of upper sections overlapping the upper edges of adjacent lower sections on the side of said sections opposite said outer layer.
